CLAIM

The ornamental design for a santa hat, as shown and described.

DESCRIPTION

FIG. 1 is a front, right side, top perspective view of a santa hat showing my new design;

FIG. 2 is a rear, left side, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front, right side, top perspective view thereof showing the top of the hat falling over toward the right side; and,

FIG. 10 is a front, right side, top perspective view thereof showing the top of the hat falling over toward the left side. The broken lines depict environment that forms no part of the claimed design for the santa hat.
